UNITED STATES PATENT OFFICE.

CORNELIUS W. GARIS, OF EASTON, PENNSYLVANIA, ASSIGNOR, BY MESNE ASSIGNMENTS, TO THE F. A. NEIDER COMPANY, OF AUGUSTA, KENTUCKY, A CORPORATION OF KENTUCKY.

BUTTON.

SPECIFICATION forming part of Letters Patent No. 736,954, dated August 25, 1903.

Application filed January 15, 1901. Renewed May 13, 1903. Serial No. 157,005. (No model.)

To all whom it may concern:

Be it known that I, CORNELIUS W. GARIS, a citizen of the United States, residing at Easton, in the county of Northampton and State 5 of Pennsylvania, have invented certain new and useful Improvements in Buttons; and I do declare the following to be a full, clear, and exact description of the invention, such as will enable others skilled in the art to which

it appertains to make and use the same.

My invention relates to improvements in buttons for upholstery and other purposes, and has for its object to provide a button composed of a single piece of wire bent to form a substantially circular head to provide for the perfect fitting of a cover thereon, suitable fastening means being provided for securing the button in place and the construction being such as to adapt the button 15 to be firmly attached and easily and cheaply manufactured.

With this and other objects in view, which will appear as the nature of the invention is fully understood, the invention consists of 25 certain novel features of construction, combination, and arrangement of parts, as will be hereinafter more fully described, and particularly pointed out in the appended claim.

In the accompanying drawings, Figure 1 is 30 a top plan view of a piece of upholstery material, showing the application of the invention thereto. Fig. 2 is a bottom plan view of the same. Fig. 3 is a sectional view thereof. Fig. 4 is a detail side elevation of the button 35 detached. Figs. 5 and 6 are top and bottom plan views thereof. Fig. 7 is a side elevation, partly in section, showing the button provided with a metallic head-cover.

Referring now more particularly to the 40 drawings, the numeral 1 represents a strip or section of upholstery material; 2, a lining or backing therefor consisting of canvas or other suitable stiffening material; 3, a washer arranged upon the under side of said stiffening material, and 4 the improved button 45 constructed in accordance with my invention. The button 4 consists, as shown, of a single piece of wire bent intermediately of its length to form a head 5 and having the ends 50 6 and 7 thereof extended to form the legs or

members of a split shank. The head 5 is formed by bending the wire substantially in the shape of the figure 8, the extremities of which project inward from opposite sides to a medial position on opposite sides of the 55 central portion or cross-bar thereof and then project downwardly and form the parallel members of the shank. In its construction the head therefore comprises a central cross-bar forming the central body portion of the wire of 60 which the head is formed and loops arranged upon opposite sides of the cross-bar, said loops extending in reverse directions from opposite ends of said bar and having their extremities inturned or projecting inwardly 65 and lying parallel with and against opposite sides of the bar upon opposite sides of a central line drawn through the head at a right angle to the cross-bar, the legs or members of the shank constituting downwardly-projecting extensions from the said extremities of 70 the loops. It will be seen that the cross-bar, loops, and inturned extremities lie in the same plane, whereby a flat head having a comparatively smooth upper surface formed 75 by parts which lie flush with each other is provided. The formation of a flat head is essential in adapting the button for upholstery-work in order that the rim edge of the head may bear squarely against the flange of the 80 metallic cap to hold the latter securely in position by direct impingement of the head thereagainst. By this construction also the opposing loops of the 8-shaped head are adapted to reinforce each other, thus providing a 85 strong and durable form of head which is not liable to spring or yield under strain and become loosened or detached from its cover, and such construction also provides a substantially circular-shaped head over which a 90 covering or shell of cloth or metal may be easily and perfectly stretched and the form thereof preserved under all conditions until worn out. As shown in Fig. 1, I may provide the head with a covering of plush, 95 leather, or other flexible or semiflexible material. I may, however, employ instead of the cloth a cap or shield-covering 9, of metal, as shown in Fig. 7, the flange of the cap being either frictionally engaged with the 100

rim of the head or crimped and indented to form to a positive locking connection therewith.

I wish it to be understood that the free ends 5 of the loops of the button are bent vertically at the central portion of the cross-bar and on opposite sides thereof to form downwardly-extended legs or prongs. By this operation of bending of the legs on opposite sides of the 10 bar an interposed space is formed between them, which extends from said cross-bar to the terminal sharp-pointed ends of said legs. By thus constructing the legs with an interposed space between them the pointed ends of 15 the legs may be forced through the material, for which purpose the button is adapted, whereby a portion of the said material will be inclosed between the legs and bear against the under side of the cross-bar when said legs 20 are bent in opposite directions, as shown in Fig. 3, by means of which the button is prevented from turning.

As shown in Figs. 1 to 3, inclusive, which 25 show the mode of employing the button in upholstery-work, the split shank of the button is forced through the covering of upholstery material and its lining and also through the underlying washer and then bent in opposite directions to lie parallel with and to 30 bear firmly against the washer to hold the head securely in place and prevent the same from being withdrawn or becoming casually displaced. When the parts or members of the shank are thus disposed, it will be seen 35 that the covered head of the button will lie in close contact with the outer surface of the upholstery material and will be held securely in place, inasmuch as the shank cannot possibly be withdrawn under any ordinary strain 40 to which the button in use may be subjected. The approximately circular form of the head

of the button adapts the shell or covering applied thereto to be perfectly fitted thereon and to preserve its shape at all times, and the non-yielding character of said head also obviates any liability of the shell or covering becoming displaced unless forcibly torn away. 45

From the foregoing description, taken in connection with the accompanying drawings, 50 the construction, mode of use, and advantages of my invention will be readily understood, and it will be seen that it provides a simple, cheap, and effective form of button for upholstering and other work where the 55 use of a firm and substantial attachment of the button is desirable. This, as well as the perfect union or connection of the cover or shell of the button with the head thereof, is secured in my construction of button in a 60 simple and effective manner.

Having thus described my invention, what I claim as new, and desire to secure by Letters Patent, is—

A button consisting of a single piece of wire 65 bent to form loops with an interposed cross-bar, the free ends of the wire being also bent vertically at the central portion of the cross-bar and on opposite sides thereof to form downwardly-extended legs or prongs, with an 70 interposed space which extends from the cross-bar between the prongs to the terminal sharp-pointed ends thereof, substantially as set forth.

In testimony whereof I have hereunto set 75 my hand in presence of two subscribing witnesses.

CORNELIUS W. GARIS.
